[57] CLAIM

The ornamental design for a stocking with checker stitched sole, as shown and described.

DESCRIPTION

FIG. 1 is a side elevational view of a first embodiment of a stocking with checker stitched sole showing my new design; the opposite side is a mirror image, the stocking is of conventional thickness;

FIG. 2 is a side elevational view of a second embodiment of a stocking with checker stitched sole showing my new design, the opposite side is a mirror image, the stocking is of conventional thickness; and,

FIG. 3 is a side elevational view of the third embodiment of a stocking with checker stitched sole showing my new design, the opposite side is a mirror image, the stocking is of conventional thickness.
